CUSHIONING MECHANISM

Hubert L. Spence, East Cleveland, and John L. Eler, Cleveland, Ohio, assignors to National Malleable and Steel Castings Company, Cleveland, Ohio, a corporation of Ohio

Application March 20, 1941, Serial No. 384,234

8 Claims. (Cl. 267—9)

This invention relates to cushioning devices, and is particularly adapted for use in railway car trucks for snubbing oscillations of the bolster.

The cushioning device to which the invention is directed comprises a plurality of levers one end of each of which is pressed against a housing by a spring acting between the housing and the other end of each of the levers. The levers are fulcrumed intermediate their ends on a follower member having wedge surfaces engaging wedge surfaces on the levers. It is an object of the invention to provide an initial contact between the wedge surfaces at or substantially at the inner end of the lever arm. As will be hereinafter set forth in more detail such a construction prevents the levers from becoming positioned at an angle to the longitudinal center line of the device such as would unduly stress the housing at the open end thereof.

Another object of the invention is the provision of means adjacent the outer ends of the levers for maintaining the contact of the spring on the levers at or near said outer ends.

A further feature of the invention is in connection with the retaining means between the levers and housing wherein a novel arrangement is provided to assure engagement of the levers with the retaining means as wear takes place between the parts.

In the drawing:

Figure 1 is an elevational view partly in vertical section of a cushioning mechanism embodying our invention.

Figure 2 is an elevational view partly in vertical section of the device, taken at right angles to Fig. 1.

Figure 3 is a horizontal sectional view, taken on line 3—3 of Fig. 1, the spring being shown in dot-dash lines.

Figure 4 is a partial plan view of the interlocking arrangement between the levers and retaining means.

Figure 5 is a partial view in vertical section, showing the initial contact between the levers and follower; and

Figure 6 is a view similar to Fig. 5, illustrating undesirable contact between the levers and follower.

The lower follower or base member 10 has a pair of oppositely sloping surfaces 11 and an upwardly projecting lug 12 formed with upwardly and outwardly sloping surfaces 13. Each friction lever 14 has a laterally extending arm 15 and a longitudinally extending arm 16. Interme-

diate the ends of arms 15 and 16 each lever has a sloping surface 17 adapted to engage one of surfaces 11 on base member 10. On the rear side of each shoe is a sloping surface 18 adapted to engage one of surfaces 13 to limit relative movement between the levers and member 10 in one direction. Arm 15 of each lever is formed at its outer end with a horizontal surface 19 and surfaces 20 sloping downwardly and outwardly 10 on each side of surface 19. A spring 21 rests on surfaces 19 of the levers and inasmuch as surfaces 20 slope away from the bottom of the spring the contact between the spring and levers is at the greatest possible distance from the fulcrum point 15 of the levers on base member 10.

A housing 22 has a flange 23 engaging one end of spring 21 and is formed with inner friction surfaces 24 in engagement with friction surfaces 25 on arms 16 of the levers. Adjacent one end 20 of the housing is a wall 26 having an opening 27 for one end of retaining bolt 28. The head 29 of the bolt is received in recesses 30 of the levers. The upper end of arm 16 of each lever is cut away at 31 to receive a flange 32 extending 25 from the opposite side of arm 16 of the other lever. As will be seen from Fig. 4, flanges 32 overlie the shank end of head 29 of the bolt and, in addition to the portions 33 of arms 16, limit upward movement of the bolt. A nut 34 on the bolt 30 bears against wall 26 to retain the housing, spring and levers in assembled relation.

As wear takes place on friction surfaces 24 and 25 the levers slide down surfaces 11 on base member 10 and the levers move farther apart. This 35 movement can continue for a considerable period without impairing the function of flanges 32 of retaining the bolt head in the levers due to the large overlap of said flanges with head 29.

Projecting upwardly from base member 10 are 40 lugs 35 which serve to position the levers laterally of the member and also are adapted to be engaged by surface 36 of the housing to transmit oversolid blows from the housing to the base member. In making the parts for our device we 45 have found that it is not practical without involving considerable expense to obtain accurate contact over the extent of surfaces 11, 17 at the same time that surfaces 24, 25 are in engagement. We therefore prefer to provide initial contact 50 between surfaces 11 and 17, as illustrated in Fig. 5, where they are shown diverging downwardly and outwardly so that the contact between the lever and base member is along a line substantially at 55 36 which is at or adjacent the inner side of the

lever. In this manner the distance from fulcrum point 36 to the point of application of the force of spring 21 at A, is at a maximum. In this position surfaces 25 of arms 16 are in contact with surfaces 24 of housing 22, and as the housing is moved downwardly friction will be developed between surfaces 24 and 25.

If the contacting surfaces 17 and 11 of the levers and base member respectively diverge upwardly and inwardly as shown in Fig. 6, the fulcrum at 37 is much closer to the point of application of force A, thus shortening the lever arm and decreasing the amount of the force of the spring transmitted to surfaces 24, 25. Moreover, we have found with surfaces positioned as shown in Fig. 6 that there is a tendency for the bottom of the levers to slide down surface 11 until surfaces 11 and 17 are in substantially complete engagement. This places arms 16 of the levers at an angle to the housing, with the result that contact of friction surfaces 25 occurs only at the bottom of the housing in the region indicated at 38. As the housing moves downwardly relative to the levers it is wedged over the levers and a bursting stress is set up around the bottom of the housing that may crack the latter member.

We have found that an angle of about three degrees between surfaces 11 and 17, as shown in Fig. 5, will assure proper initial contact between the parts. In any event, it is undesirable to start out with contact between surfaces 11, 17 as shown in Fig. 6. It will be understood that some wear will take place on surfaces 11 and 17 and eventually these surfaces may be in substantial engagement as shown in Fig. 1. However, so long as these surfaces diverge so that the initial contact is toward the inner part of the lever, as shown in Fig. 5, there will be no tendency of the levers to slide down surfaces 11 so as to be at an angle to the housing member and place said member under bursting stresses.

As normal wear occurs on the friction surfaces of the housing and levers the latter will slide down surfaces 11 on the base member so as to maintain proper area of contact between surfaces 24 and 25. It will be observed that clearance is provided between spring 21 and the outer surface 39 of the levers so that the latter may move outwardly as wear takes place on the friction surfaces.

The terms and expressions which we have employed are used as terms of description and not of limitation, and we have no intention, in the use of such terms and expressions, of excluding any equivalents of the features shown and described or portions thereof, but recognize that various modifications are possible within the scope of the invention claimed.

What we claim is:

1. In a cushioning mechanism a base member having a plurality of plane surfaces thereon sloping upwardly and toward the center thereof, friction levers each having a plane surface initially engaging one of said first named surfaces only near the upper extremity thereof, each of said levers having a pair of arms substantially at right angles to each other, spring means operatively engaging one of said arms, and a housing having a flange engaging said spring means and interior surfaces frictionally engaging the other of said arms.

2. A cushioning mechanism having a base member with upwardly inclined surfaces, friction levers supported by said base member hav-

ing upwardly inclined surfaces, a housing engaging one end of said levers, spring means between the other end of said levers and said housing, said inclined surfaces on said base

5 member and levers diverging downwardly and outwardly so as to maintain the initial contact therebetween at the inner end of said surface on the levers and so as to initially provide clearance between the outer ends of said surface on each lever and the corresponding inclined surface on said base member.

10 3. A cushioning mechanism having a base member with upwardly inclined surfaces, friction levers supported by said base member each 15 lever having a surface inclined upwardly at a different angle than said first named surfaces, a housing engaging one end of said levers, spring means between the other end of said levers and said housing, the angle between said 20 surfaces on said base member and levers being such that the initial contact therebetween is at the inner extremity thereof so as to provide fulcrums for said levers removed as far as possible from the line of engagement of said spring 25 means and levers.

4. A cushioning mechanism for railway cars comprising a base member, friction levers slidably mounted on said base member, a housing frictionally engaging one end of said levers, a spring between the other end of said levers and said housing, retaining means having an enlarged end engaging said levers and an end engaging said housing, and means on the upper end of each of said levers adjacent said enlarged 35 end extending from one of said levers into overlapping relation with another of said levers to maintain the lever engaging end of said retaining means in position.

40 5. A cushioning mechanism for railway cars comprising a base member, a pair of friction levers slidably mounted on said base member, a housing frictionally engaging one end of said levers, a spring between the other end of said levers and said housing, retaining means having 45 an enlarged end engaging said levers and an end engaging said housing, and integral means on the upper end of each of said levers adjacent said enlarged end extending from each of said levers into overlapping relation with another of said levers 50 of said levers to maintain the lever engaging end of said retaining means in position.

6. A cushioning mechanism for railway cars comprising a base member, a pair of friction levers slidably mounted on said base member, a housing frictionally engaging one end of said levers, a spring between the other end of said levers and said housing, said levers being recessed on their inner sides, a retaining bolt having a head received in said recess, said housing 55 having a transversely extending wall provided with an opening receiving said bolt, and integral means on the upper end of each of said levers extending laterally of said bolt into overlapping relation with the opposite lever to maintain said head in said recess.

60 7. A cushioning mechanism comprising a base member having upwardly and inwardly inclined surfaces thereon, friction levers supported by said base member each lever having an arm extending laterally outwardly and an arm extending vertically upwardly, a housing engaging said 70 vertically extending arms, and spring means operatively engaging said laterally extending arms and said housing, said levers initially engaging said inclined surfaces towards the upper 75

extremity thereof and being spaced from said surfaces towards the lower extremity thereof.

8. In a cushioning mechanism a base member having a pair of oppositely sloping surfaces thereon, friction levers engaging said surfaces, each of said levers having a vertically extending arm and a laterally extending arm, a housing frictionally engaging said vertically extending arms, spring means between said housing and said laterally extending arms, said levers initially engaging said sloping surfaces toward the

upper extremity thereof and being spaced from said surfaces towards the lower extremity thereof, the upper surface of said laterally extending arms comprising a substantially horizontal central portion engaging said spring means and a surface on each side of said central portion sloping downwardly away from said spring means.
